UNITED STATES PATENT OFFICE.

MIRABEAU N. LYNN AND ELMORE P. LYNN, OF RISING SUN, INDIANA,
ASSIGNORS TO THE LYNN ENGINE COMPANY, OF DAYTON, OHIO.

STEAM-ENGINE.

SPECIFICATION forming part of Letters Patent No. 377,462, dated February 7, 1888.

Application filed July 20, 1886. Renewed June 22, 1887. Serial No. 242,151. (No model.)

To all whom it may concern:

Be it known that we, MIRABEAU N. LYNN and ELMORE P. LYNN, both of Rising Sun, in the county of Ohio and State of Indiana, have 5 invented certain new and useful Improvements in Steam-Engines; and we do hereby declare the following to be a full, clear, and exact description of the same, reference being had to the accompanying drawings, forming part of 10 this specification, and to the figures and letters of reference marked thereon.

This invention relates to improvements in the arrangement, location, and means for operating the valves of engines of the direct-acting multiple-cylinder class, as hereinafter described, and pointed out in the claims.

In the accompanying drawings, Figure 1 is a longitudinal vertical section of a two-cylinder engine, showing our improvements applied thereto. Fig. 2 is an end view, partly in section, of said engine. Figs. 3 and 4 are enlarged sectional views of the piston and valve in different positions. Fig. 5 is a transverse sectional view of the valve and piston on line 25 x x , Fig. 4, looking toward the head of the cylinder.

Similar letters of reference in the several figures indicate the same parts.

With the exception of the pistons and valve 30 mechanism, the engine shown, and which is simply introduced to illustrate one mode of applying our present invention in practice, is in all material respects substantially the same in form and construction as that described in 35 our joint application, Serial No. 188,722, filed January 16, 1886.

A is the main casing and A' the cylinders.

A^2 is the removable head, carrying the governor A^3 and throttle-valve A^4 , and provided 40 with steam-passages a , leading to the jackets of the cylinders.

A^5 is the crank-shaft, A^6 the counter-weight, and A^7 the pitman.

Steam or other fluid under pressure is admitted through an opening, a' , in the lower cylinder communicating through a cored passage, a^2 , in said cylinder with a passage in the head A^2 , leading to the steam-chest a^4 of the throttle-valve. This mode of connecting 45 the steam-pipe with the steam-chest is preferred, as it permits the head A^2 to be removed 50

without disconnecting the steam-pipe; but, if desired, the steam-pipe connection may be made directly with the steam-chest of the throttle-valve.

As shown at Fig. 1, the steam passes directly from the throttle-valve into the jackets of the cylinders, from whence it is introduced into the cylinders above the pistons in the following manner: Within each piston P , of 6c which more than two may be employed, if desired, is formed a chamber, C , for the reception of a valve, V , controlling inlet and exhaust ports v v' , communicating with the interior of the cylinder above the piston, and at 15 a point intermediate the ends or heads P' P^2 of the piston is formed a passage, E , communicating with the said valve-chamber C . The opposite ends, P' P^2 , of the piston P are provided with packing-rings, so that the steam- 70 passage E , preferably surrounding the piston, divides the latter into three sections comprising the two ends or pistons P' P^2 and the connecting portion P^3 , less in diameter than the pistons P' P^2 , within which the valve is located. Steam is admitted to the passage E , and thence to the valve-chamber C in the piston, through a series of ports or openings, R , in the inner wall of the cylinder and communicating with the steam-space therein. 75

The preferred form of valve is that shown, consisting of upper and lower sections, U U' , provided with parallel faces u , fitting the opposite faces of the valve-chamber, as shown. The upper section, U , of the valve is provided with a cylindrical or other shaped portion, u^2 , fitting within a sleeve, u^3 , on the lower section, and in it is formed the passage or passages p , leading from the exhaust-port d^3 , while the lower section, U' , is formed with 85 a large opening, p^2 , for establishing and maintaining a free passage for the exhaust-steam into an opening or openings, p^3 , in the lower portion, P^2 , of the piston, and communicating with the central chamber of the main casing. 90 The two sections U U' as thus constructed and arranged constitute, practically, a balanced valve; but owing to the rapid motion of the pistons it is found desirable in practice that the valve should not be completely balanced, 95 but that a sufficient area should be exposed on each section to hold them pressed against their 100

seats and prevent their being thrown off by the inertia of the parts.

In one section of the valve, preferably the upper, is formed a tubular guide, G, for the 5 reception of a block, g, in which is pivoted the end of an arm, M, connected to and forming an extension of the head of the pitman A', which latter is pivotally attached to the lower section, P², of the piston.

10 The upper section of the valve is so adjusted and proportioned relative to the inlet and exhaust ports in the piston, the throw of the crank, and the length of the arm or connection between the pitman and valve that at 15 mid-stroke of the valve, which occurs as the crank passes the center, the inlet will be opened and the exhaust closed, or vice versa, as the piston reaches the limit of its stroke in either direction; hence the movement of the 20 valve to admit and exhaust the propelling fluid in the cylinder must be the same, but in a reverse direction at each end of the stroke of the piston. This arrangement is amply sufficient when the engine is to be used as a 25 meter or hydraulic motor, in which event three cylinders should be employed; but if designed to be driven by steam it is desirable that some provision be made whereby the supply of steam can be cut off during the latter 30 part of the stroke of the piston; and with this end in view we have so arranged and located the openings or ports in the cylinder relative to the length of the piston and crank that the piston itself shall operate as a cut-off valve. 35 As before stated, the piston proper is provided with two piston-heads, P' P², between which is formed, in connection with the cylinder, a steam-space communicating with the valve-chamber and inlet-port. The openings 40 or ports in the wall of the cylinder are so located with respect to the upper or outer piston-head, P', that when the piston is at the outer end of the cylinder steam will be delivered into the steam-space between the two 45 piston-heads, and as the piston is forced upward toward the crank the upper or outer piston-head will lap over and cover the ports or openings in the cylinder, thereby cutting off the supply and allowing the steam in the cylinder to act expansively upon the piston. 50

The point of cut-off can be regulated and determined by changing the location of the openings in the cylinder or the position of the piston-head relative to said openings. As shown 55 in the drawings, the piston is arranged to cut off at about one-half stroke.

By forming the openings through which steam is admitted to the cylinder at equal distances apart the pressure upon the periphery 60 of the piston is equalized.

Having thus described our invention, what we claim as new is—

1. The combination, with a cylinder having 65 ports or openings in its inner surface for the admission of steam, of a piston carrying a valve controlling the inlet and exhaust ports, said piston being provided with two piston-

heads and a steam-space between them, into which steam is delivered from the openings in the cylinder, substantially as described. 70

2. The combination, with the cylinder and its openings or ports, of a piston carrying the valve mechanism governing the inlet and exhaust openings and provided with a steam-space intermediate the ends of the piston and 75 communicating with the valve-chamber, said steam-space co-operating with openings in the cylinder during a portion only of the stroke of the piston to thereby limit the supply of steam as delivered to the cylinder, substantially as 80 described.

3. The combination, with the cylinder having steam openings or ports in its interior, of a piston having a valve-chamber and valve through which the steam is admitted and exhausted in the cylinder, said piston being also provided with a steam-space intermediate its ends or heads, whereby steam is admitted to the valve-chamber at the beginning of the stroke and is cut off by the movement of the 90 piston which closes the ports in the cylinder during the latter portion of the stroke, substantially as described. 85

4. In a direct-acting steam-engine such as described, wherein steam is admitted direct to 95 the interior of the cylinder through ports in the side thereof, and in combination with said cylinder, a piston carrying valve mechanism controlling the admission and escape of steam above the piston and operating in conjunction with the ports in the cylinder as a cut-off, 100 substantially as described.

5. In an engine such as described, and in combination with the cylinder and its ports or 105 openings, the piston provided with two piston-heads connected together to form a steam-space and valve-chamber, and a valve located in said chamber and driven by the pitman to alternately open and close the inlet and exhaust ports as the crank passes the center, 110 substantially as described.

6. In an engine such as described, and in combination with the cylinder having ports or openings, the piston fitting the cylinder above and below said openings or ports and 115 provided with an intermediate steam-passage for re-establishing communication between the said ports or openings and an inlet-port in the piston, substantially as described.

7. In a direct-acting steam-engine, and in 120 combination with the piston thereof provided with the valve-chamber, as described, the slide-valve constructed in two sections fitted together and engaging the opposite faces of the valve-chamber, the inlet and exhaust ports 125 formed in one end of the piston and the exhaust-port in the other, said valve-sections being also provided with a passage through their connecting portions for the escape of the exhaust through the piston, substantially as described. 130

8. The combination, in a direct-acting engine such as described, and with the piston and cylinder thereof, of a slide-valve located

in the piston and provided with a longitudinal socket for the reception of a guide-block, the pitman pivotally secured to the lower side of the piston, and the rod attached to and forming an extension of the piston projecting within the piston and valve with its end pivoted to the before-mentioned guide-block in the valve, substantially as described.

9. In a direct-acting engine such as described, and in combination with the cylinder having openings or ports in its inner walls, and a piston provided with two heads and an intermediate steam-space and operating as a cut-off, a valve carried by said piston and moving in unison with the pitman to control the admission of steam from the steam-passage into the cylinder above the piston and the escape of steam through the piston, substantially as described.

10. In a direct acting steam-engine such as described, wherein steam is admitted through openings in the cylinder and into a steam-space in the side of the piston during a portion of the stroke and cut off during the remainder of the stroke by the end of the piston overlapping the openings in the cylinder, and in combination with said piston and cylinder, a valve-chamber formed in the piston, and a slide-valve located in said chamber, moving in unison with the pitman and exhausting through the rear end of the piston, substantially as described.

11. In a direct-acting steam-engine such as described, and in combination with the piston provided with double heads and an intermediate space, a cylinder provided with a series of openings or ports arranged at equal distances apart, through which the fluid is admitted to the interior of the cylinder, whereby, when the head of the piston is brought opposite said openings to serve as a cut-off, the pressure will be equalized upon the periphery of the piston, as set forth.

12. In a direct-acting engine such as described, and in combination with the jacketed cylinder having openings or ports in its inner walls, the piston provided with two heads and an intermediate space through which the fluid is conducted from the openings in the cylinder to the valve in the piston, the reciprocating valve containing the exhaust-passage communicating with the opening in the lower end of the piston, and the pitman pivotally attached to the piston in said last-mentioned opening and carrying an arm or extension engaging the valve to reciprocate the latter, substantially as described.
